DESIGN FOR AN INFANT'S SANDAL

Berce L. Veach, St. Louis, Mo.

Application November 21, 1946, Serial No. 134,969

Term of patent 7 years

(Cl. D7—7)

To all whom it may concern:

Be it known that I, Berce L. Veach, a citizen of the United States, residing in the city of St. Louis and State of Missouri, have invented a new, original, and ornamental Design for an Infant's Sandal, of which the following is a specification, reference being had to the accompanying drawing, forming a part thereof.

In the drawing:

Fig. 1 is a top or plan view of an infant's sandal, showing my new design;

Fig. 2 is a side perspective view thereof; and

Fig. 3 is a side elevational view of the opposite side of the sandal in Fig. 2.

I claim:

The ornamental design for an infant's sandal, substantially as shown.

BERCE L. V EACH.
